SUPPORT FOR PAPER ROLLS

Thomas A. Webber, 6408 Stratford Road,
Chevy Chase, Md.

Filed Aug. 5, 1965, Ser. No. 86,455

Term of patent 14 years

(Cl. D4—3)

FIG.1

FIG.2

FIG.3

FIGURE 1 is a perspective view of a support for paper rolls, showing my design;

FIGURE 2 is a side elevational view thereof; and

FIGURE 3 is a transverse vertical section on line 3—3 of FIGURE 2.

The end surface of the article at the left hand end of FIGURES 1 and 2 is flat and plain.

I claim:

The ornamental design for a support for paper rolls, as shown and described.
